UNITED STATES PATENT OFFICE.

CARL A. WENDELL, OF JOLIET, ILLINOIS.

COAL-WASHING APPARATUS.

1,165,734.

Specification of Letters Patent. Patented Dec. 28, 1915.

Application filed March 8, 1915. Serial No. 12,919.

To all whom it may concern:

Be it known that I, CARL A. WENDELL, a citizen of the United States, residing at Joliet, in the county of Will and State of Illinois, have invented certain new and useful Improvements in Coal-Washing Apparatus, of which the following is a specification.

My invention relates to coal washing apparatus and has particular reference to a novel apparatus wherein pulsations are created by means of extremely low pressure air and without need for a vacuum.

In the operation of washing coal in order to remove therefrom the slate and other impurities it is not uncommon to employ an agitator in connection with a body of water whereby a concentrating action is secured. This operation is frequently carried out in connection with a bed of material such as feldspar superposed on a screen through which the particles of slate and such materials may pass.

My improvement relates to means for causing the agitation of the water and materials at a minimum cost the result being secured without the use of water plungers, gearing, shafting, and so forth with the result that an extremely economical and efficient apparatus is provided.

The invention is predicated upon the assumption that the reciprocation of the water may be caused by air pressure, the pressure being alternately reduced and restored to atmospheric. This air pressure, although relatively small, acts upon a comparatively large area and therefore causes the reciprocation or agitation of the body of water with ease.

The invention will be more readily understood by reference to the accompanying drawings, wherein—

Figure 1 is an elevation partly in section on the line 1—1 of Fig. 2 showing a device constructed in accordance with my invention; and Fig. 2 is a plan view thereof.

Referring more particularly to the drawings, it will be seen that on the supports 10 I mount an outer hopper-like casing 11 having an inwardly and upwardly inclined top 12 apertured at intervals to register with air supply pipes 13, these pipes connected with a header 14 which is in turn connected to an exhaust fan, not shown. A simple form of valve is shown in Fig. 1 by means of which the required pulsating action is

secured. This valve may consist in a valve proper 15 controlled by a plunger 16, the valve being caused to reciprocate vertically by the cam 17. This valve is in a sense only diagrammatic of means for creating a pulsating action on the air, and as the valve forms no part of the present application its details need not be described or shown.

Located within the outer casing 11 is a hopper-like inner casing 18 within which a screen 19 is located near the top. The top 20 of the casing 18 is slightly above the cover 12 of the outer casing. The lower end of the inner casing is open and registers with a container 21 into which the refuse is directed and from which it may be removed by actuating the slide valves 22—23. Between the inner and outer casings and located near the top thereof is a plunger in the form of a flat ring 24 to which suitable bellows 25 are connected, the upper ends of the bellows being fastened to angles and plates 26 having a water-tight connection to the walls to which they are secured. It thus follows that the space above the ring 24 and the bellows 25 is water-tight and acts as a dome or air drum.

In operation water is supplied to the two containers through the pipes 27 until it overflows the top 20 of the casing 18. A bed of feldspar or similar material is supplied to the screen 19 and thereafter the coal to be washed which has previously been crushed is supplied to the axial center of the screen. Preferably the weight of the ring 24 and its associated parts is equal to the weight of water corresponding to the difference in height between the lower edge of the plunger 24 and the top edge 20 of the hopper 18. This results in a balanced condition, and a very slight reduction of air pressure within the chamber above the plunger results in raising the plunger by the added weight of water in the inner shell. Reversely the restoration of the pressure conditions within the chamber causes the elevation of the water and its discharge over the edge of the container 18. Inasmuch as these fluctuations in pressure are intended to follow each other with extreme rapidity the material on the screen 19 will be agitated and the heavier particles of slate or refuse will stratify and pass through the feldspar bed and through the screen dropping to the lower portion of the container. The washed coal and the water are discharged

around the top 20 of the inner container and flow down into the chute or spill-way 28 being discharged at 29 from which point the material is taken to a sump or mechanical driers. If the weight of the plunger member does not exactly balance the weight of water within the inner container, additional weight may be added thereto by utilizing the pockets or recesses 30 in the 10 upper edge of the ring 24.

By use of an apparatus such as described substantially all friction losses are eliminated, the only friction developed being that of the water and air in their respective containers. 15

Obviously the construction is capable of much modification and such modification as is within the scope of my claims I consider within the spirit of my invention. 20

20 I claim:

1. In a coal washing device, the combination of concentrically arranged containers, the outer of which is sealed to the atmosphere, a plunger within said outer container, 25 said plunger adapted to prevent the passage of water thereby, a screen within said inner container, means for pneumatically acting upon the plunger in said sealed container and thereby causing a pulsation of the water 30 within said inner container and the agitation of the material on the screen, substantially as described.

2. In a coal washing jig, the combination of adjacent containers adapted to receive 35 washing liquid, the top of one of said containers being sealed to the atmosphere, a freely vertically reciprocable plunger within said sealed container, a bellows connecting said plunger to said containers said bellows 40 adapted to prevent the passage of water by said plunger, and pneumatic means for causing the reciprocation of said plunger thereby causing a pulsation of the water within said

inner container and the agitation of the material on the screen, substantially as de- 45 scribed.

3. In a coal washing jig, the combination of a pair of concentrically arranged shells the outer of which is sealed to the atmosphere, a plunger within said outer shell near 50 the top thereof, a bellows yieldingly connecting said plunger to said shells, said bellows adapted to prevent the passage of water by said bellows and said plunger, said plunger being of a size capable of acting 55 upon an area of liquid substantially equal to the area of the inner shell whereby the liquid is maintained at unequal heights in the two containers, and pneumatic means for causing the reciprocation of said plunger 60 and thereby the agitation of liquid within said inner container, substantially as described.

4. In a coal washing jig, the combination of axially arranged containers the outer of 65 which is sealed to the atmosphere, a plunger and a bellows, said plunger and bellows separating the upper portion of said outer container and forming a pneumatic chamber, means for supporting a body of coal within 70 said inner container, and pneumatic means acting in said air chamber to periodically reduce and increase the pressure within said chamber whereby said plunger is caused to reciprocate and agitate the water in the 75 inner and outer containers, said water and washed coal being discharged over the outer edge of said inner container, substantially as described.

In witness whereof I have hereunto signed 80 my name in the presence of two subscribing witnesses.

CARL A. WENDELL.
